UNITED STATES PATENT OFFICE.

GEORGE GRAY, JR., OF PHILADELPHIA, PENNSYLVANIA, ASSIGNOR TO LARGMAN,
GRAY COMPANY, OF CROYDON, PENNSYLVANIA.

MACHINE FOR MAKING DISPLAY CARDS.

Application filed March 6, 1926. Serial No. 92,983.

This invention relates to new and useful improvements in machines for producing display cards and more particularly to a machine for threading a card with display tape or braid.

The primary object of the invention resides in providing a machine through the medium of which cards may be produced upon which are displayed varied colored 10 tapes or braid adapted to correspond in color and shade with certain wearing apparel, such as silk hosiery.

Ladies silk hosiery is sold in varied colors and shades which vary slightly, each shade 15 being known by a particular name which is most difficult for the public to remember and it becomes extremely difficult for anyone to order a particular shade of hosiery without seeing a specimen thereof. A card 20 displaying these various shades of tape and braid, corresponding in shade to the various colors and shades of hosiery to be purchased, will be extremely useful, beneficial and valuable to both the retailer and the customer, inasmuch as it will save considerable 25 time and labor in endeavoring to locate the particular shade of garment desired and will produce satisfaction to all parties concerned.

The machine forming this invention and 30 constituting the basis for this application produces the aforementioned card and while I have referred to the same as being applicable to use in providing cards displaying the colors and shades of hosiery, it will 35 be understood that the display of colored tape or braid on the card may be applicable to the sale of other materials in the piece or to other garments, as may be found desirable.

40 A further object of the invention resides in providing an improved means for feeding cards to a position where a plurality of varied colored tape or braid may be automatically threaded therethrough and a still 45 further object resides in providing means for automatically positioning the cards in the machine so as to be properly threaded through a continuous operation of the machine.

50 A still further object resides in providing a simple, efficient and improved means for threading the tape through the cards as the latter are fed in position, with an effective

means for holding the tape during the threading operation to prevent stretching of 55 the tape at such times.

Still another object resides in the provision of an improved and automatic cutting means for severing the tape after the same 60 has been threaded through the card.

Another object resides in the provision of an improved timing mechanism whereby in the continuous feeding of cards to and 65 through the machine, the various elements will be successively actuated to feed the cards, intermittently operate an endless carrier, hold the tape against certain cards, thread said tape through certain cards and sever said tape at predetermined intervals.

With these and numerous other objects in 70 view, which it appears unnecessary to refer to in detail at this time, my invention consists in the novel features of construction, combination and arrangement of parts as will be hereinafter referred to and more particularly pointed out in the specification and claims.

In the accompanying drawings forming a part of this application,

Fig. 1 is a side elevation of my machine, 80 illustrating the drive connections.

Fig. 2 is a front elevation of the machine.

Fig. 3 is a top plan view thereof.

Fig. 4 is a vertical longitudinal section therethrough as seen on the line 4-4 of 85 Fig. 3.

Fig. 5 is a vertical transverse section through the machine as seen on the line 5-5 of Fig. 1, and

Fig. 6 is a plan view of one of the cards, 90 completed and removed from the machine.

In describing the invention I shall refer to the drawings in which similar reference characters designate corresponding parts throughout the several views and in which numeral 1 designates a support of any preferred character, such as a table or the like, upon which the machine is adapted to be mounted. This machine may be driven by any source of power, such as an electric motor (not shown) and in the drawings I have shown a drive belt 2 leading from the source of power and operating over a pulley 3 carried on the one end of a drive shaft 4. This drive shaft is supported in bearings 5 carried at the upper ends of brackets 6,

the latter being suitably supported on a table or support 1.

Mounted on the drive shaft 4 is a worm 7 which meshes with a worm wheel 8 loosely carried at one end of what I term for convenience a cam shaft 9. This cam shaft is rotatably supported in brackets 10 which are in turn mounted on the base frame 11 of the machine. The worm wheel 8 is provided on its one face with one section of a disc clutch 12, the opposite section thereof being carried by the shaft 9, and a coil spring 13 obviously forces the worm wheel 8 in such position as to enable the sections of the clutch to become effective normally. Should, for any reason whatsoever, the machine become clogged, as for instance by reason of the failure of certain elements to work properly, the clutch 12 may be readily disengaged by drawing outwardly upon the worm wheel 8 against the tension of the spring 13, which quickly and readily disconnects the power.

Mounted in bearings 14 at the upper ends of the vertical supporting brackets 10, is a transverse driven shaft 15 which carries a drum 16, the latter being formed integral with said shaft or keyed thereto, as may be desired. This drum 16 is pentagonal in cross section for a purpose to be hereinafter and more particularly described.

A rear idle shaft 17 is rotatably mounted in bearings at the upper ends of the rear vertical brackets 18 which are carried at the rear end of the frame 11. Formed on, or otherwise secured to the idle shaft 17, are the pentagonal sprockets 19 which are designed to conform to the cross sectional structure or design of the drum 16. An endless carrier designated generally by the numeral 20 operates over the drum 16 and sprockets 19 for the purpose of feeding and conducting the cards to a position whereby the tape, or silk, may be threaded therein. This endless carrier consists of end links 21 forming two side chains and connected by transverse slats or plates 22, the latter forming supports for the cards to be carried through the machine. Each plate has provided on its rear edge one or more hook-like flanges 23 which hold the card in position with respect to the plate 22 and the end links on the one side of the machine have secured thereto the stop blocks 24, which limit the movement of the cards in one direction with respect to the carrier. These stop blocks 24 are removably and adjustably mounted on the end links of the carrier, as clearly shown in Fig. 3 of the drawings.

The cards which are adapted to be fed to the machine are designated in the drawing by the numeral 25, the same being rectangular in plan, having the side edges provided at regular intervals with slits 26 into which the braid or tape is to be forced. The trans-

verse plates 22 of the carrier 20 have their longitudinal edges provided at regular intervals with grooves 27 which are adapted to correspond and align with the slits in the cards 25 when the latter are placed on the carrier. These grooves are of such width as to accommodate slits which may not be provided at exact intervals apart, it being understood, of course, that in the manufacture of the cards there may be some inaccuracies and further, the cards may be of different lengths with slightly different variations in the spacing of the slits.

Mounted on the end of the shaft 9 opposite that carrying the worm wheel 8 is a crank arm 28 which pivotally connects with a pitman 29, the latter in turn being pivotally connected with an arm 30 oscillatingly mounted on the one end of the shaft 15. The arm 30 is mounted for oscillation intermediate of its ends and the end thereof opposite that having connection with the pitman 29 has a dog 31 pivotally connected thereto which is adapted to be normally forced under the action of a spring 32 into engagement with the teeth of a ratchet 33, said ratchet being carried on the shaft 15. Obviously, from this construction, said shaft 15 will be rotated intermittently upon the rotation of the shaft 9. Mounted on the opposite end of the shaft 15 is a second ratchet 34, the teeth of which are engaged by a pivotally supported dog 35 held in position by means of a coil spring 36. Through the medium of this last mentioned pawl and ratchet connection, backlash in the shaft 15 will be prevented.

As stated previously, the object of this invention is to provide a machine for producing cards upon which may be displayed braid or tape of various colors which are designed to correspond to colors of wearing apparel, such as hosiery, so that a manufacturer may display and sell his goods through the medium of these display or color cards. The tape or braid used for this particular purpose may be fed from spools carried on brackets (not shown) and in the drawings I have designated the tape by the numeral 37. This tape 37, of which there are as many strands as there are colors to display, is adapted to be guided through openings 38 formed in a guide bar 39, the latter being preferably carried above the machine by a support 40, the latter forming actually the feed device for the cards, which will be described in detail here below. The tape 37 is further guided downwardly toward the machine through openings in a second guide bar 41, the latter being of an inverted U shaped design and adjustably supported at the upper ends of a pair of upstanding pivotal arms 42. These arms are pivotally supported at their lower ends to the side rails of the frame 11 as shown at 43 and said arms

42 are adapted to be rocked at pre-determined times during the operation of the machine in the manner to be hereinafter and more particularly described.

5 The tape after being guided through the openings in the guide bar 41 is disposed over a roller 44 which is supported between the upper ends of the arms 42, said roller tending to flatten the braid or tape. Arms 45 10 fulcrumed intermediate their ends on the arms 42 have disposed between their upper ends a roller 46 which is adapted to cooperate with the roller 44 in flattening the braid or tape. The lower ends of the arms 45 15 have connected therewith the ends of coil springs 47, the opposite ends of said coil springs being engaged with the brackets 10, so that when the arms 42 are rocked rearwardly, the rollers 44 and 46 are in contact 20 with one another, while the roller 46 will be released from contact when the arms 42 are rocked forwardly.

Pivoted supported on the arms 45, below the roller 46, are the links 48 which support between their outer ends another roller 49, the latter by gravity resting upon the tape or braid 37, as it passes between the rollers 44 and 46, thus tending to take up the slack in said tape or braid.

30 As stated previously, the arms 42 are adapted to be rocked upon their pivots and said arms are connected by means of a transverse bar 50, shown in dotted lines in Fig. 1. A longitudinal rod 51 is pivoted at its 35 rear end to an upstanding pivotal arm 52 mounted at the rear end of the frame 11 and the forward end of said rod is connected with a cam 53 mounted on the cam shaft 9. A pair of spaced lugs 54 are carried on the rod 50 40 and obviously when said rod 51 is moved forwardly and rearwardly under the action of the cam 53 the lugs 54 will come in contact with the rod 50 and rock the arms 42 45 for the purpose above mentioned.

As the tape continues from under the roller 49 the same is guided through openings formed in a transverse guide bar 55, the latter being removably and adjustably supported in a plane below the horizontal plane of the roller 49 by means of the vertical arms 56 which are movably secured to the rear edges of the brackets 10. Adjustably and removably secured to the arms 56, and extending rearwardly therefrom, are the supporting pieces 57 between which is adjustably and removably held a transverse bar 58. Removably secured to this transverse bar 58 are a plurality of compoundly bent 55 spring fingers 59, the forward and free ends of which rest in contact under spring tension with the card mounted on the carrier just in advance of the card which is being threaded with the tape. These fingers dragging on the card not only hold this card in

position on the plate 22 of the carrier, but also tend to drag the card rearwardly so as to retain it in contact with the holding flanges 23.

Also suspended removably below the guide 70 bar 55 is a transverse bar 60 which supports thereon the ends of a plurality of forwardly projecting and downwardly inclined guide fingers 61, the outer ends of which are slotted to receive therethrough 75 the tape or braid 37, as clearly illustrated in Fig. 4 of the drawings. In order to prevent this tape or braid from moving from side to side in the slots of said fingers I provide a retaining rod 62 which rests on the 80 tape just below the slots in said fingers and is held in yielding contact with the under faces of said fingers by means of the spring wires 63. These wires are secured at their ends to the bar 60 and to the retaining rod 85 62. The slots in the fingers 61 are in vertical alignment with the slits 26 in the cards 25.

In first starting the machine, the first 90 card reaching the drum 16 is manually threaded by the operator so as to engage the tape or braid in the slits of said card, but I have provided an automatic means for carrying out this process which I shall describe in detail. In order to carry out this 95 automatic threading means it is necessary to construct the drum 16 with a plurality of longitudinal key ways or slots 64 which are formed therein at the corners thereof, as clearly shown in Fig. 4 of the drawings. 100 The faces forming this pentagonal drum 16 are provided with spaced apart transverse slots 65 which are adapted to align with the slits 26 in the cards 25 and correspondingly align with the slots at the ends of the guide 105 fingers 61.

In describing the threading of the cards with this tape or braid, it also becomes necessary to describe in detail features which assist in maintaining the cards in position. 110 devices which prevent the undue elasticity of the tape, and other detailed structures necessary in effectively carrying out this procedure. Mounted in bearings 66 projected forwardly from the brackets 10, is a rock shaft 67 upon which are adjustably mounted a pair of arms 68. Removably secured to the outer ends of the arms 68 is a transverse rubber press member 69 which, when said arms are moved rearwardly, is adapted 115 to contact with the tape or braid on the card facing forwardly on the drum to prevent said tape or braid being unduly stretched while the same is being threaded through the slits in the cards.

Also adjustably mounted on the shaft 67 are the downwardly and rearwardly projecting operating arms 70, the free ends of which have rollers 71 supported thereon. These 120 rollers are normally held in frictional contact 130

with a pair of cams 72 mounted on the cam shaft 9. A coil spring 73 engages with the shaft 67 and the one bracket 10 normally retains the rollers 71 in yielding contact with the cams 72. As the cams are rotated with the shaft 9, the shaft 67 will be correspondingly rocked to cause the press member 69 at predetermined times to contact with the tape on the one card, as shown in dotted lines in Fig. 4 of the drawings.

Also mounted in bearings 74 above the bearings 66 is a second rock shaft 75 which has mounted thereon a pair of upstanding arms 76. Connected with the outer ends of these arms 76 and removably secured thereto, is a threading bar 77 which is adapted to be forced downwardly and inwardly at predetermined times and received in a slot 64 of the drum 16. The machine is so constructed and timed to permit this bar 77 to be received in the slot forward and uppermost in said drum as the latter is rotated. The bar 77 is provided at regular intervals throughout its length with a plurality of outstanding fingers or projections 78 which, when the bar is forced downwardly, will contact with the series of tapes or braids and force the latter through the slits in the two adjacent edges of the cards on the upper and forward faces of said drum.

Carried on and projected downwardly from the shaft 75 are the arms 79 which have rollers at the lower free ends thereof resting in contact with cams 80 carried on the cam shaft 9. A coil spring 81 engaged with a projection on the shaft 75 and also engaged with the bracket 10, normally retains the rollers on the arms 79 in yielding contact with the cams 80.

Slidably and yieldingly supported on the upper outer face of the threading bar 77 is a presser bar 82 which is adapted to engage the tape or braid as it is fed from the fingers 61 and press the same against the upper face of the card supported on the upper face of the drum 16 just prior to the threading operation. In the normal position of this presser bar its lower free edge projects beyond the outer free edges of the threading fingers 78 so that it appears obvious that the series of tape or braid will be held firm when the threading fingers engage said tape or braid.

It is apparent from this construction that as the machine is in operation the cards will be conducted forwardly on the carrier 20 and upon reaching the drum 16, the machine is timed to start the threading operation. First, the arms 68 are rocked rearwardly so that the rubber press member 69 engages the tape or braid on the outer foremost face of the drum 16, as shown in dotted lines on Fig. 4, whereupon the arms 76 are rocked rearwardly causing the press member 82 to engage the tape extending from the

fingers 61 and forcing said tape downwardly against the face of the card positioned on the upper face of the drum 16. Continuing in operation the press bar 77 is forced downwardly into the slot 64 positioned between the last two mentioned faces of the drum 16 and the threading fingers 78 will respectively engage and force downwardly and inwardly the series of tapes or braids extending across said slot. When forced downwardly and inwardly in this manner, these tapes or braids are forced through the slits 26 in the cards 25, the grooves 27 in the plate 22 and the transverse slots 65 in the drum 16 readily permitting this to be accomplished.

Further continuing in operation the arms 68 and 76 and their adjunctive parts, are rocked forwardly permitting the carrier to move forwardly and move another card in position to be threaded and simultaneously conduct the last card threaded to be carried to a position where the tape or braid may be severed. It may be here stated that when the threading operation takes place, the arms 42 are rocked so that the rollers 44 and 46 contact tightly against the series of tapes or braids holding the same taut.

Fulcrumed on the shaft 67 is an arm 83 which may be termed a presser arm, the fulcrumed point being intermediate of its ends. The one end of this arm may be free and supports a bracket carrying presser rollers 84 which are adapted to contact with the card on the forward lower face of the drum 16, as clearly shown in Fig. 4. These rollers are held in yielding contact with the card by means of a coil spring 85 which has its one end connected to the forward end of the arm 83 and its opposite end connected with the frame 11, as shown in Fig. 2 of the drawings.

These rollers 84 retain the one card in position on the drum when the tapes have been severed from the preceding card. This is necessary, otherwise the card would drop downwardly from the drum 16 and not be in position to be acted upon by the cutters which will be described here below.

Vertically movable in slots 86 formed in the brackets 10 is a cutter bar 87 which has suspended there below a pair of rollers 88. These rollers are adapted to contact with cams 89 carried on the shaft 9. The cutter bar 87 carries a plurality of rigid blades 90 to which are fulcrumed a plurality of pivotal blades 91, the free ends of the latter being pivotally connected to a laterally movable actuated bar 92. This bar 92 is guided and suspended in bearings 93 carried on the bar 87.

Coil springs 94 connected with the cutter bar 87, and with the frame 11, normally tend to draw the cutter bar downwardly, but said bar is moved upwardly at pre-determined

times by the action of cams 89 and when moved upwardly the blades of the cutter enter the lowermost positioned slot 64 in the drum 16. These blades 90 and 91 when in raised position straddle the series of tapes or braids and when the bar 92 is actuated will sever said tapes or braids.

In order to actuate the bar 92 I provide a rocker arm 95 which is pivotally supported on the frame 11 on a horizontal axis so as to project upwardly and the upper end of this arm is slotted to receive therein a bolt 96 projected forwardly from the actuated bar 92. Mounted on the shaft 9 is a cam 97, while a roller 98 mounted on the arm 95 is normally adapted to contact with the face of said cam as a result of inaction of a coil spring 99 which connects at its one end with the upper end of the arm 95 and at its other end with the one bracket 10. This coil spring is more clearly illustrated in dotted lines in Fig. 2 of the drawings.

The machine is constructed and timed so that when the cards which have been threaded have reached a particular position on the drum, the cutter bar will be raised and the cutters actuated to sever the tape, whereby the card may drop downwardly to a chute or receptacle (not shown).

In order to prevent any interference with the cutters as a result of possible sagging of the links of the carrier I provide the supporting rollers 100 which are carried by pivoted arms 101 mounted on the brackets 10. These arms 101 are yieldingly held in position by means of the coil springs 102, clearly shown in Fig. 4.

As stated previously, the member, designated as 40, forms a vertical housing or magazine in which the cards are disposed and from which the same are fed to the machine. This housing 40 is open at its bottom but adapted to be closed by means of a sliding feed plate 103. This plate is guided in slots formed in guide plates 104 mounted on the rear brackets 18, and standing from the rear of the plate is a lug 105. A link 106 is pivotally connected with this lug 105, it has its end slotted as shown at 107. Connected with the slotted end of the link 106 is the upper end of the rocker arm 52, previously described. A coil spring 108 connects the upper end of the arm 52 with the lug 105. The upper face of the plate 103 at its forward end is offset the thickness of one of the cards 25, this offset forming a shoulder designated by the numeral, 109. It will thus be seen that as the plate 103 is drawn rearwardly upon the action of the arm 52 the lowermost card in the housing 40 will be received in the offset portion of said plate, said cards being forced downwardly by means of gravity and also by means of a weight 110. As the rocker arm 52 is drawn forwardly the plate 103

will be moved forwardly and position the lowermost card in the offset portion to a point beyond the chamber 40. As the rocker arm 52 is moved rearwardly it will draw upon the spring 108 but will not immediately draw the plate 103 therewith. When the tension of the spring 108 becomes great it will snap the plate 103 rearwardly with considerable force and permit the card in the offset portion thereof to drop vertically downward and rest upon one of the plates 22 of the carrier 20. Were it not for the particular action of this spring 108, the dropping card would not be properly positioned on the carrier.

In order to further assist in properly positioning the card on the carrier, after it is dropped thereon, I provide an additional set of compoundly curved spring fingers 111 which are carried on the forward end of the guide 104, as clearly shown on Figs. 1 and 4 of the drawings.

From the foregoing description of the construction of my improved machine, the operation thereof will be readily understood and it will be seen that I have provided a simple, comparatively inexpensive, and efficient means for carrying out the objects of the invention.

While I have particularly described the elements best adapted to perform the functions set forth, it is obvious that various changes in form, proportion and in the minor details of construction may be resorted to, without departing from the spirit or sacrificing any of the principles of the invention.

Having thus described my invention what I claim is:

1. In a machine of the class described, means for feeding cards therethrough, and means for threading display tape through and across the face of said cards to lay flat upon the latter.

2. In a machine of the class described, means for conveying blanks therethrough, means for guiding display tape to a predetermined position on said machine and means for threading said tape through and across said blanks to lay flat upon the face of the latter.

3. In a machine of the class described, means for conveying blanks therethrough, means for guiding display tape to a predetermined position on said machine, means for threading said tape across the face of said blanks and means for severing said tape from the blanks.

4. In a machine of the class described, a carrier adapted to convey a series of blanks through said machine, means for automatically feeding and applying display tape across the face of said blanks as the carrier is actuated.

5. In a machine of the class described, a

carrier adapted to convey a series of blanks through said machine, means for automatically feeding and threading display tape across the front face of said blanks as the carrier is actuated and additional means for severing said tape from the rear face of said blanks.

6. In a machine of the class described, a carrier adapted to convey a series of blanks through said machine, means for automatically feeding and threading display tape to and across the front face of said blanks as the carrier is actuated, and automatically operated cutting means for severing said tape from the rear face of said blanks subsequent to the threading operation.

7. In a machine of the class described, a carrier adapted to convey a series of blanks through said machine, means for automatically feeding and threading display tape to said blanks as the carrier is actuated, means for holding said tape to the blanks prior to and during the threading operation, and means for severing the tape from said blanks subsequent to said threading operation.

8. In a machine of the class described, a carrier adapted to convey a series of blanks through said machine, means for automatically directing said blanks to a predetermined position on the carrier as the latter is actuated, and means for automatically feeding and threading display tape to and across the face of said blanks as the latter reach predetermined positions in the movement of the carrier.

9. In a machine of the class described, a carrier, means for actuating the same intermittently, means for automatically feeding blanks to said carrier and means for automatically feeding and threading tape in said blanks at predetermined intervals.

10. In a machine of the class described, a carrier, means for actuating the same intermittently, means for automatically feeding blanks to said carrier, means for automatically feeding and threading tape in said blanks at predetermined intervals and at predetermined positions with respect to said carrier, and means for severing said tape from said blanks subsequent to the threading operation.

11. In a machine of the class described, an endless carrier adapted to convey blanks through said machine, means for intermittently actuating said carrier, means for guiding tape to said blanks, a threading member actuated at predetermined times upon the actuation of said carrier for threading said tape in said blanks and a cutting element for severing the tape from said blanks operated automatically upon the actuation of said threading member and subsequent to the latter.

12. In a machine of the class described, a carrier adapted to convey blanks through

said machine, means for intermittently actuating said carrier, means for guiding tape to said blanks on the carrier, means for holding the tape to said blanks actuated indirectly from the carrier operating means, means for threading said tape in said blanks during the tape holding operation, said last mentioned means being also actuated indirectly from the carrier operating means and additional means for severing said tape from the blanks following the threading operation.

13. In a machine of the class described, a carrier adapted to convey blanks through said machine, means for intermittently actuating said carrier, a drum over which said carrier operates, said drum being provided with radial grooves, means for guiding tape to the blanks on said carrier, means for holding the tape to said blanks, threading arms actuated indirectly from the carrier operating means for forcing the tape through said blanks, grooves in said drum receiving said arms therein, and means for severing said tape from the blanks following the threading operation.

14. In a machine of the class described, a frame, a carrier supported thereon, adapted to convey blanks through said machine, a cam shaft supported on said frame below the carrier, means actuated from said cam shaft to intermittently actuate said carrier, tape guiding means mounted on said machine, means actuated from said cam shaft to hold the tape to said blanks at predetermined times, additional means actuated from said cam shaft to thread the tape through said blanks subsequent to the last mentioned means, and means for severing said tape from the blanks following the threading operation, said severing means being also actuated from said cam shaft.

15. In a machine of the class described, a frame, an endless carrier supported thereon, a cam shaft supported on said frame below said carrier, means for driving said cam shaft, means actuated from one end of said cam shaft for intermittently operating said carrier, said carrier being adapted to convey blanks through said machine, means for guiding tape to the blanks on said carrier, means actuated from said cam shaft for holding the tape to the blanks, additional means actuated from said cam shaft for threading the tape through said blanks at predetermined times, means supported on said frame immediately below one end of said carrier and actuated by said cam shaft for severing the tape from the blanks at predetermined times, and means for retaining succeeding blanks to the carrier following the aforesaid severing operations.

16. In a machine of the class described, a frame, an endless carrier supported therein comprising a pair of chains, transverse

- plates connecting the same, said plates being provided at their edges with spaced apart grooves, a rotatable drum having a plurality of flat faces over which said chains operate, said drum at the intersection of the faces being provided with longitudinal slots intersected by transverse grooves adapted to register with the grooves at the edges of said plates, said plates being adapted to convey blanks through the machine, means for guiding tape to said blanks and means adapted to engage said tape and enter the aforesaid slots and grooves for threading said tape in said blanks.
17. In a machine of the class described, a carrier adapted for conveying perforated blanks thereon, and means for applying display tape across the face of said blanks and threading same through the perforations of said blanks to be displayed from the face 20 of the latter.
18. In a machine of the class described, a carrier for conveying blanks thereon, said blanks being perforated at the side edges thereof and means for threading display 25 tape through the perforations of said blanks to be displayed across the face of the latter.
19. In a machine of the class described, a carrier for conveying blanks thereon, said blanks being perforated inwardly from the 30 side edges thereof to form slits, and means for applying display tape to the face of said blanks and threading the same through the perforations thereof.

In testimony whereof I affix my signature.

GEORGE GRAY, JR.
